UNITED STATES PATENT OFFICE.

LYMAN GOLD, OF CHARLESTOWN, INDIANA.

AUTOMATIC GRAIN CUT-OFF.

1,129,085.

Specification of Letters Patent. Patented Feb. 23, 1915.

Application filed March 17, 1913. Serial No. 754,889.

To all whom it may concern:

Be it known that I, LYMAN GOLD, a citizen of the United States, residing at Charlestown, in the county of Clark and 5 State of Indiana, have invented certain new and useful Improvements in Automatic Grain Cut-Offs, of which the following is a specification.

This invention relates to automatic grain 10 cut-offs for use in various places about mills, elevators, distilleries, and other buildings where grain is handled in measured quantities, and the object of the invention is to supply a predetermined quantity of grain, 15 by weight, to tempering machines or other receptacles, and coincidentally for supplying steam or water or both to said tempering machine and to automatically cut off the steam or water supply with the cutting off 20 of the supply of grain.

Another object of the invention is to provide an electric alarm bell or signal which will give warning to the operator when the grain has ceased to flow.

25 I accomplish the above and other minor objects of the invention to be hereinafter pointed out, by the mechanism illustrated in the accompanying drawings in which—

Figure 1 is a perspective view of my complete invention in operative position to supply a measured quantity of grain to a wheat steamer. Fig. 2 is a view in side elevation and vertical section of the invention on a larger scale. Fig. 3 is a side elevation 30 of the grain receiving and measuring cylinder as seen looking from the rear. Fig. 4 is a front elevation in partial section of the steam and water valves and their connections, and Fig. 5 is a perspective view of the 35 lower end of the inner or valve cylinder which controls the discharge from the cylinder shown in Fig. 3.

40 Like characters of reference indicate like parts throughout the several views of the drawings.

45 My invention is supported by and from a frame comprising the vertical posts 6 and horizontal members 7. Mounted upon the front upper horizontal member 7 is a stand- 50 ard to which a horizontal lever 8 is pivot- ally secured.

55 9 is a grain receiving cylinder having a bail 10 with a pair of ears 11 between which the lever 8 is pivotally secured, as shown in Fig. 2, whereby the cylinder 9 will be sus- 60

pended from the lever 8 and capable of ver- 65 tical adjustment within the limits of the swinging movement of said lever. Pivotally secured to the outer end of the lever 8 is a depending rod 12 which supports weights 13. The weights 13 are removable and are varied to counterbalance the cylinder 9 and its contents up to a predetermined limit fixed by said counter-weights 13.

The cylinder 9 terminates with a hopper-shaped bottom 14 having a cylindrical central outlet 15. The inner walls of the hopper bottom 14, particularly at their junction at the cylindrical discharge 15, comprise the seat for a valve which is also a cylindrical body 16 located within the cylinder 9, and having a hopper-shaped bottom 17 with a depending flange or band 18 of a diameter to make a loose sliding fit within the cylindrical discharge 15, of the larger cylinder 9. 75 Fixed within the smaller cylinder 16 is a cross-bar 19 to which a vertical rod 20 is adjustably secured by means of nut 21 below and nut 22 above bar 19, on the screw-threaded end of the rod 20. The upper end 80 of the rod 20 is fixed to a stationary cross-bar 24 fastened to the undersides of the horizontal members 7 of the main frame of the machine. The upper end of the rod 20 is screw-threaded and receives a nut 25, 85 below the bar 24 and a nut 26 above said bar and these two nuts provide means for additionally adjusting the valve-cylinder 16 in its distance from the rod 24. Radial arms 27 carried by the cylinder 16, contact 90 with the inner walls of the cylinder 9 to keep the cylinder 16 centered within the cylinder 9. The cylinder 16 is provided with a conical cap 28 to prevent the entrance of grain into the valve cylinder 16. Grain is 95 supplied to the interior of the cylinder 9 through the pipe 29, and discharges in the manner shown in Fig. 2. When the cylinder 9 is empty it will be at its maximum elevation with the angle between parts 14 and 15 100 in such relation to the flange 18 of the valve 16 that no discharge from the cylinder 9 will occur. But as the quantity of grain and its weight in the cylinder 9 is increased by the supply coming through the pipe 29, 105 this weight will overbalance the counter-weight 13 on the outer end of the lever 8 causing the loaded cylinder 9 to descend by gravity. The lowering of the cylinder 9 will cause a discharge opening to occur at 110 its bottom because of the fixed condition of the valve cylinder 16 and its parts by its sus-

pension from the stationary bar 24, and the grain in the cylinder 9 will begin to spill out through the bottom opening thus formed.

5 The lower end of the valve cylinder 16 is centered by means of a wire basket-like formation comprising a plurality of radial wires 30 having vertical stems 31, the upper ends of which are secured to the inner side 10 of the sleeve or band 18 (see Figs. 2 and 5). This wire basket fits into the cylinder 15 and does not obstruct the discharge of grain through the latter. To keep the grain from discharging too fast through the opening at the bottom of cylinder 9, and also to obviate any possibility of the grain clogging so as to prevent the upward return movement of the cylinder 9, I provide a curtain of heavy ducking 33 which is wrapped 15 around the outside of the flange 18 and is secured to said flange. A considerable width of this material extends below the limits of the flange 18, and this portion is provided with vertical slits 34 at suitable 20 intervals to form tongues 35 which will swing inwardly under the pressure of the grain above it, allowing the grain to discharge past them. The lower ends of the tongues 35 are made pointed, as shown, to 25 make their action additionally sensitive.

Vertical guide rods 36 fastened to the diametrically opposite walls of the cylinder 9 at front and back of the latter are held by grooved wheels 37, a pair for each rod, 30 mounted in vertical members 38 supported by the cross timbers 7. An overflow of spout 39 (see Fig. 3) communicates at its upper end with the interior of cylinder 9 to carry off any excess of grain that may 35 accidentally be supplied to the cylinder at any time. I have shown the spout 39 as provided with two connections 40 and 41, at 40 different heights, with the interior of cylinder 9 and communication through them is 45 regulated by sliding valves 42.

The grain discharges from cylinder 9 into a trough 43, and is conveyed by said trough to a tempering machine or any other suitable receiver. I have here shown the trough 43 as discharging into a steamer 44. It is generally desirable to subject the grain to regulated quantities of water, or steam and in many cases to the action of both water and steam, and it is a part of my invention to provide means operated by the grain weighing mechanism, for supplying the required amount of moisture or steam or both to the tempering machine 44. To this end I provide a valve 45 to which water is supplied through a pipe 47, and I also provide a valve 46, preferably located close to the valve 45, to which steam is supplied to a pipe 48. The water from valve 45 discharges through pipe 49 into the steamer or 55 tempering machine 44, as shown in Fig. 1,

and the steam is discharged from the valve 46 through the pipe 50 to the machine 44. Valves 51 in the supply pipes 47 and 48 and valves 52 in the discharge pipes 49 and 50 provide the means for cutting off the supply to the machine 44 through either set of pipes when desired. 70

Mounted in each of the valves 45 and 46 is a plunger 53, the outside upper ends of which are pivoted to a corresponding lever 75 54. The inner end of each lever 54 is pivoted to a bracket 55, and the outer end of each lever 54 is connected by a corresponding rod 56 with the reduced ends of a cross head 57 carried by the lever 8, whereby, 80 when the outer arm of the lever 8 is moved upwardly by the weight of grain in the cylinder 9 the levers 54 will be moved in like direction to lift the plungers 53 and open up communication through the valves 45 and 46 between their water and steam supply and discharge pipes, as above described. The valves 45 and 46 are mounted on a plate 85 58 which is supported by brackets 59 from the vertical post 6. 90

In order to delay the opening of the water and steam valves until after a given quantity of grain has accumulated in the cylinder 9 I make each rod 56 in two transversely divided parts. The adjacent ends 95 of these two parts of each rod are screw-threaded, as shown in Figs. 2 and 4, and the lower ends of the upper parts are screwed into threaded holes in respective turn buckles 60. The threaded ends of the lower 100 parts of said rods 56 are passed loosely through suitable unthreaded holes in the lower ends of the respective turn buckles 60, and a nut 61 is first screwed upon said threaded ends, and after the insertion of the 105 ends through the holes in the turn buckles 62 is placed, as shown, to prevent the withdrawal of the rod. The nuts 61 and 62 can be placed at any desired position on their rod. 110

When the cylinder 9 drops down about one quarter of an inch the inside lower end of the swivel 60 engages the nut 62 and begins to lift the plunger 53 opening the valve. These two parts, cylinder 9 and nut 62, are 115 timed with the lift of the plunger so as to cause their valves to discharge the proper amount of steam or water to moisten the corresponding amount of grain passing out of cylinder 9. When the cylinder 9 is discharging a proper quantity of grain its further travel downward is prevented by the connection here shown. The turn buckle 60 engages with nut 61 in the upward travel of cylinder 9, which seats the plunger 53. The 120 levers 54 are provided with depending rods 63 bearing weights 64 to regulate the action 125 of the levers. 130

The outer end of the lever 8 is provided with a terminal plate 65, and supported in

its path is a terminal 66. These terminals 65 and 66 are connected in the usual manner with a signal bell 67 by wires 68 and in the circuit is a battery 69 and a knife switch

5 70. When the cylinder 9 is sufficiently empty to cause the outer end of lever 8 to drop bringing the terminals 65 and 66 together and closing the electric circuit through wire 68 the bell 67 will ring and 10 will continue to ring until the circuit is broken by again weighting the cylinder. When it is desired to discontinue the use of the bell the circuit is broken by opening the switch 70.

15 While I have described my invention with more or less minuteness as regards details of construction and arrangement and as being embodied in certain precise forms, I do not desire to be limited thereto unduly 20 or any more than is pointed out in the claims. On the contrary, I contemplate all proper changes in form, construction and arrangement, the omission of immaterial elements, and the substitution of equivalents, as circumstances may suggest or necessity render expedient.

I claim:

1. A pivoted lever, a grain holding receptacle suspended from one end of the lever, 30 said receptacle having a discharge opening at its lower end, the outer end of the lever being weighted to counterbalance the receptacle, a closure closing the discharge opening in the receptacle when the latter is in 35 its highest position, means by the lowering of the receptacle from the closure for opening its discharge, means for steaming and dampening the discharged grain, and means connected with the lever for operating said 40 steaming and dampening means.

2. A pivoted lever, a grain holding receptacle suspended from one end of the lever, said receptacle having a discharge opening at its lower end, the outer end of the lever 45 being weighted to counterbalance the receptacle, a closure for closing the discharge opening in the receptacle when the latter is in its highest position, means by the lowering of the receptacle from the closure for 50 opening its discharge, a receiver for the discharged grain, steam and water pipes discharging into said receiver, valves to regulate the discharge through said pipes, and means connecting said valves with said pivoted lever to open and close the valves by 55 the swinging movement of the lever.

3. A pivoted lever, a grain holding receptacle supported by the lever, said receptacle having a discharge opening at its lower end, 60 counter-weights at the opposite end of the lever from the receptacle, a closure for the discharge opening in the receptacle, means by the lowering of the receptacle for opening the discharge at its bottom, a receiver for the discharged grain,

means for supplying steam and water to the receiver, and means connected with the lever for regulating the supply of steam and water to the receiver.

4. A pivoted lever, a grain holding receptacle supported by said lever, said receptacle having a discharge opening at its lower end, counter-weights at the other end of the lever from the receptacle, a closure supported in a fixed position to close the discharge opening 70 into the receptacle when the latter is in its highest position and to open the discharge to the bottom of the receptacle by the lowering of the receptacle, and means connected with and operated from said lever for steaming and dampening the discharged grain.

5. A pivoted lever, a grain holding receptacle suspended from one end of the lever, said receptacle having a hopper-shaped bottom with a central discharge opening, 85 counter-weights at the other end of the lever, a closure for the discharge opening through the bottom of the receptacle, means for retaining a fixed position of the closure whereby the discharge from the receptacle 90 may be opened by the lowering of the latter, a receiver for the discharged grain, means for supplying steam and water to the receiver, and means connecting said steam and water supply means with said pivoted lever 95 to regulate said supply by the swinging movement of the lever.

6. A pivoted lever, a grain holding receptacle suspended from one end of the lever, said receptacle having a discharge opening 100 at its lower end, a closure for the discharge opening in the receptacle, means for the lowering of the receptacle for opening the discharge through the bottom of the receptacle, a receiver for the discharged grain, 105 steam and water pipes discharging in said receiver, valves to regulate the discharge through said pipes, and means connecting said valves with said pivoted lever to open and close the valves by the swinging movement of the lever, said means comprising a two-part rod having adjacent threaded ends, a turn-buckle screwed to one of said threaded ends, the other threaded end passing loosely through an opening in the opposite end of 110 the turn-buckle, and spaced-apart nuts on said last threaded end, one on each side of the adjacent end of the turn-buckle.

7. A pivoted lever, a grain holding receptacle suspended from one end of the lever, 115 means to vary the contents of the receptacle to move the lever on its pivot, an electric circuit, current supplying means in said circuit, a signal bell in said circuit, a terminal at the opposite end of the receptacle in said circuit, an opposite terminal also in said circuit adjacent said last terminal but held in a fixed position whereby, by the upward movement of the lever the circuit will be 125 opened, and whereby said circuit will be 130

closed by the lowering of the outer end of the lever occasioned by the emptying of the receptacle, and means connected with and operated by said lever for steaming and 5 dampening the discharged grain.

In witness whereof, I have hereunto set my hand and seal at Charlestown, Indiana,

this 8th day of March, A. D. one thousand nine hundred and thirteen.

LYMAN GOLD. [L. S.]
